UNITED STATES PATENT OFFICE.

WILLIAM CLEMSON, OF MIDDLETOWN, N. Y., ASSIGNOR TO THE WHEELER,
MADDEN & CLEMSON MANUFACTURING COMPANY, OF SAME PLACE.

SAW-HANDLE.

SPECIFICATION forming part of Letters Patent No. 257,657, dated May 9, 1882.

Application filed February 11, 1882. (Model.)

To all whom it may concern:

Be it known that I, WM. CLEMSON, of Middletown, in the county of Orange and State of New York, have invented certain new and useful Improvements in Crosscut-Saw Handles; and I do hereby declare the following to be a full, clear, and exact description of the invention, such as will enable others skilled in the art to which it pertains to make and use the same.

10 My invention relates to an improvement in crosscut-saw handles, the object of the same being to provide means whereby the plane of the saw can be changed from the same plane as the handle to a position or plane at right angles thereto, or vice versa, without disengaging the saw from its fastening-bolt or removing the shank from the handle; and with these ends in view my invention consists in certain details in construction and combinations of parts, as will be more fully explained, and pointed out in the claims.

In the accompanying drawings, Figure 1 is a side view, showing the saw secured to the handle in the same plane therewith. Fig. 2 is a similar view, showing the saw secured in a plane at right angles to the handle. Fig. 3 is a longitudinal sectional view of the saw as shown in Fig. 1, and Fig. 4 shows detached views in perspective of the shank.

30 A represents the handle, provided with the lower extension, A', and the shoulder a, against which the socket or eye B bears. This socket or eye B is adapted to fit snugly on the extension A' and up against the shoulder a, and is provided near its lower end, on one side, with the angular or square opening b, in which the angular or squared shoulder c of the shank C rests, and on the opposite side with the round opening b', through which the round screw-threaded end of the said shank protrudes. That portion of the socket or eye B surrounding the opening b is slightly increased in size to afford increased bearing for the socket, and that portion of the socket or eye surrounding the opposite hole or opening can also be increased in size and provided with a flat surface to afford a firm bearing for the thumb-nut D.

35 C is the shank, which consists of the rectangular body portion d and the round screw-thread-

ed portion d', which latter is adapted to pass through the opening b through an opening in the extension B' of the handle, and thence through the opening b' on the opposite side of the socket or eye. The extreme inner end of the body portion d, or that portion nearest the round part d' of the shank C, is squared off, and is adapted to snugly fit and be removably secured within the opening b of the socket B in such a manner that no motion whatever is allowed the said shank C. The face E' of the rectangular portion of the shank C is provided with a longitudinal groove, g, running nearly throughout the entire length of the said rectangular portion, for the reception of one edge 65 of the saw F. The rectangular or body portion of the shank C is provided with the enlarged portions e and the laterally-extending portion e' for the reception of the clamping-bolt G. This clamping-bolt G is provided with the longitudinal slit h, running nearly throughout its entire length, and with the screw-threaded end h', on which the thumb-nut b' moves to secure the saw in position. The downwardly-extending portion e' of the shank 75 C affords ample lateral bearing for the clamping-bolt G and prevents the same from wabbling from side to side or holding the saw at an inclination instead of in a horizontal or vertical plane.

80 When it is desired to secure the saw to the handle with its saw-teeth downward, as shown in Fig. 1, it is only necessary to loosen the thumb-nut b' and lower the clamping-bolt until enough of the slit h is above the shank E to admit of the passage of the end of the saw. When the end of the saw has been placed in position the thumb-nut b' is screwed home, which firmly holds the saw in position. If desired, the upper and lower edges of the saw-blade can be provided with depressions, in which the upper curved end of the clamping-bolt can rest, and which will aid in preventing the saw from being withdrawn from the slot. After the saw has been secured to the shank, and it is desired to change its position relative to the handles, the thumb-nut D is first unscrewed until the shoulder c clears the sides of the opening b, when the handle can be turned until the saw is presented at right angles to 95 the shank, and the thumb-nut D is again screwed home. If it is desired to change the position of the saw relative to the handle, the thumb-nut b' is first unscrewed until the shoulder e' 100

the handle, with the teeth on either side thereof, or until the handle has been turned half around, which will leave the saw in the same plane with the handle, but with the teeth presented in the opposite direction, when it is secured by screwing up the thumb-nut D.

My improved handle is simple in construction, easily and quickly manipulated, can be manufactured at small cost, and is adapted to hold the saw therein without displacement.

It is evident that slight changes in the construction of the different parts might be resorted to without departing from the spirit of my invention, and hence I would have it understood that I do not limit myself to the exact construction of parts shown and described, but consider myself at liberty to make such changes as come within the spirit and scope of my invention.

Having fully described my invention, what I claim as new, and desire to secure by Letters Patent, is—

1. The combination, with a handle and an eye or socket secured thereto, the latter being provided with an angular opening or recess on one side and an opening on the opposite side for the passage of the end of the shank, of a shank having means for securing the saw-blade thereto, and provided with an angular shoulder of the same size as the angular recess before referred to, and with a screw-threaded portion adapted to pass through the handle and through the opening on the opposite side of the eye or socket, and means for securing the said shank in position, substantially as set forth.

2. The combination, with a handle and an eye or socket secured thereto, the latter being provided with an angular recess on one side and provided on the opposite side with an

opening for the passage of the end of the shank, 40 of a shank consisting of a body portion and a screw-threaded end portion, the body portion being provided with a longitudinal groove for the saw to rest in, and an angular shoulder adapted to fit in the angular opening in the 45 said eye or socket, as described, and means for securing the saw-blade to the said shank, substantially as set forth.

3. The combination, with the saw-handle provided with a socket having an angular 50 opening or recess on one side and an opening on its opposite side, of a shank constructed to extend through the socket and provided with an angular portion that fits within the angular recess in the socket and with a groove to receive the edge of the saw-blade, and a clamping-bolt and thumb-nut for securing the saw-blade to said shank, substantially as set forth. 55

4. The combination, with the saw-handle provided with a downward extension, an eye 60 or socket, B, provided with an angular opening or recess on one side and an opening on its opposite side, of a screw-threaded shank inserted through the socket and secured by a thumb-nut, and constructed with an angular 65 portion that fits in the angular opening of the socket, said shank being provided with a groove, g, and a projection, e', and the clamping-bolt G and thumb-nut b², substantially as set forth.

In testimony whereof I have signed this specification in the presence of two subscribing witnesses.

WM. CLEMSON.
